PRODUCE BASKET

Walter R. J. WOOCK, Lodi, Calif.

Application December 19, 1949, Serial No. 6,726

Term of patent 14 years

(Cl. D58—4)

To all whom it may concern:

Be it known that I, Walter R. J. WOOCK, a citizen of the United States, residing at Lodi, in the county of San Joaquin and State of California, have invented a new, original, and ornamental Design for Produce Basket, of which the following is a specification, reference being had to the accompanying drawing, forming a part thereof.

I claim:

The ornamental design for a produce basket, as shown.

WALTER R. J. WOOCK.
